UNITED STATES PATENT OFFICE.

GIDEON Efraim Sandblom, of Gottenborg, Sweden.

APPARATUS FOR REMOVING BOILER-SCALES.

1,181,616.

Specification of Letters Patent.

Patented May 2, 1916.

Application filed October 29, 1915. Serial No. 58,649.

To all whom it may concern:

Be it known that I, GIDEON Efraim Sandblom, engineer, a subject of the King of Sweden, residing at Gottenborg, in the Province of Gottenborg and Bohus and Kingdom of Sweden, have invented new and useful Improvements in Apparatus for Removing Boiler-Scales, of which the following is a specification.

10 This invention refers to apparatus for removing of scales or the like from boiler plates, especially from the interior surfaces of the shell of cylindrical boilers.

The object of the invention is to employ 15 a cheap, simple and reliable device, adapted to be advantageously used in narrow spaces as well as in all other compartments in the boiler. Also my said implement is convenient to use for cleansing of the outer 20 surfaces of boiler tubes as well as the plating of ship's hull or the like.

Another object of this invention is to provide a scale removing device which may be used even by persons not particularly 25 skilled in the handling of such apparatus and to assist the user in applying effective blows on the plate to be treated.

The invention comprises a rapid revolving shaft provided with a plurality of short 30 chains or similar flexible members such as wire ropes, arranged in straight lined or spiral rows along the shaft, said shaft being caused to revolve by the influence of some driving motor. As the driving motor I prefer 35 for a small electric machine adapted to be conveniently held by hand by the workman. To increase the efficiency of the apparatus the chains or flexible members are provided at their free end with a chipper or hammer 40 preferably with sharp edges. I use the device in such a way that the shaft is caused to quickly revolve and thereby is held in the vicinity of the plate to be treated, parallel with same so that the free ends of the 45 flexible members respectively their chippers or hammers are caused by the centrifugal force to strike the plate with very often repeated blows until the scales or incrustations are knocked off.

50 The device forms a readily manipulated self-contained mechanism which is, as a whole, rigid and can be inserted through a man-hole or the like and held firmly adjacent to the part it is desired to clean.

55 In the accompanying drawing Figure 1

is a cross section of the shaft showing the chains stretched out in working position. Fig. 2 is a side view of the chipper or hammer. Fig. 3 is a section through a boiler illustrating the use of the improved device 60 when introduced in a rather narrow space. Fig. 4 is a side view of the complete apparatus provided with an electric driving motor and Fig. 5 is a similar view of the machine in a somewhat modified embodiment. 65

The shaft *a* is provided with a plurality of short chains *b* fixed at their one end to the shaft *a* in an easily detachable manner by means of a split pin *d*, introduced through a transverse boring in the shaft and bent over at the rear end in the usual way. By this means any arbitrary chain can be easily removed when necessary to replace it with a fresh device. The chains may be arranged in rows along a suitable length of the shaft 75 *a* and may be set in straight lines or helical rows.

I do not limit myself to the special embodiment illustrated in the drawing but may replace the chains *b* with steel wire ropes or other suitable flexible members but I prefer to use short chains, comprising circular links as I understand them to be best suited for the work. The circular shape of the links decreases the wear and tear of the link iron, as 85 the one link will be free to slide all around the neighboring link, as will not be the case if oblong or usual chain links were used, because it is not possible in such shaped links for the one link to move but on a rather 90 limited portion of the neighboring link, causing this to be very quickly worn out.

In the free end of each chain or flexible member there is suspended a chipper or hammer *c*, preferably of the form clearly illustrated in the Figs. 1 and 2 and provided with a rather sharp edge *l* around the outermost end, in the vicinity of which the center of gravity of the hammerbody is situated, far from the suspension end for the purpose 95 of increasing the influence by the centrifugal force when revolving the shaft with the chains swung freely around same.

The shaft *a* projects from an electric motor *e*, provided with a handle *f* by means 105 of which the apparatus is readily manipulated inside the boiler *h*. In very narrow spaces, such for instance between the boiler shell *h* and a stay *g*, it sometimes happens that the device cannot be introduced so far 110

as necessary, and to overcome these difficulties the shaft α may be prolonged rather extensively which however would decrease the efficacy of the apparatus on account of the 5 flexibility of the thin shaft. Such vibrations may be avoided by surrounding the revolving shaft α on the length between the motor e and the working end with a tube i (Fig. 5) attached to the motor e in any suitable 10 way. A certain amount of lateral motion of the rather long shaft α may be allowed by means of a universal joint m .

One of the important features of my improved instrument is to be found in its 15 adaptability to suit narrow spaces, such as illustrated in Fig. 3. In such places the flexible members b get wound around the shaft α , thus automatically adjusting their length so as not to injure the plates by too 20 hard blows but to soften same just as needed.

The mode of attaching the chains b on to the shaft α by means of the split pins d insures a handy replacing of worn chains by

fresh ones and consequently the cleaning work can be continued without undue delay. 25

Having thus described my said invention and how the same is to be performed what I claim as new and desire to protect by Letters Patent is:

An apparatus for removing incrustations 30 comprising a rigid rotatable shaft, a motor directly mounted on the end of said shaft so as to form an integral portable member therewith, a plurality of independent chain members connected at their inner ends to 35 said shaft and formed of circular links, and a conical shaped chipping member attached to the outer end of each chain member having a sharp circular cutting edge at its outer end.

In witness whereof I have hereunto set my hand in the presence of two witnesses.

GIDEON EFRAIM SANDBLOM.

Witnesses:

GUSTAF SERTI,
ADOLF MOLIN.
